United States Patent Office.

LEWIS SCOTT, OF SINKING SPRING, OHIO.

Letters Patent No. 95,049, dated September 21, 1869; antedated September 10, 1869.

IMPROVED PAN AND FURNACE FOR EVAPORATING.

The Schedule referred to in these Letters Patent and making part of the same.

To all whom it may concern:

Be it known that I, LEWIS SCOTT, of Sinking Spring, in the county of Highland, and State of Ohio, have invented a new and useful Improvement in Vaporizing-Furnace and Pans; and I do hereby declare that the following is a full, clear, and exact description thereof, which will enable those skilled in the art to make and use the same, reference being had to the accompanying drawings, forming part of this specification.

This invention relates to a furnace and an arrangement of pans for boiling and vaporizing juice or sirup in the process of making sorghum sugar or molasses, and for other purposes of a similar nature; and

The invention consists in the peculiar construction and arrangement of the pans and furnace or stove, whereby the contents of the pans are protected from undue heat or burning, and whereby the stove or furnace is adapted to ordinary cooking-purposes, as will hereinafter be described.

Figure 1 is a vertical section of a furnace for vaporizing liquid, which furnace is used in the first part of the process, the section being through the line *xx* of fig. 2.

Figure 2 is a top or plan view.

Figure 3 is a vertical cross-section of fig. 1, through the line *yy*.

Figure 4, sheet 2, is a vertical longitudinal section of a furnace or stove, of a construction similar to that represented in sheet 1, but with the pans arranged differently, and designed to be used in perfecting or finishing the process of vaporization, the section being through the line *zz* of fig. 5.

Figure 5 is a sectional top view of the same, the front part being broken away to show the interior of one of the pans, and the back or left-hand portion being a view from the line *z'z'* of fig. 1.

Figure 6 is a vertical section of one of the pans, through the line *yy'* of fig. 7.

Figure 7 represents a broken section of a perforated bottom pan.

Similar letters of reference indicate corresponding parts.

The views given on the two sheets of drawings are designed to represent but a single furnace, the second being a modification adapted to the finishing-process, but provided with a detachable oven, to be used when the stove is in use for cooking-purposes.

A represents the furnace, or stove, which is made of metal, and placed on legs, and arranged otherwise similar to an ordinary cooking-stove.

B is the upper pan, where the process of vaporization is commenced.

C represents a pan, which is placed directly over the fire-box of the furnace, into which the liquid from the upper pan is drawn, through the tube *d*.

To prevent the liquid in the pan B from burning, a double flue is provided for the products of combustion.

e is a horizontal partition-plate in the fire-flue, placed directly under the pan B.

f is a flap-damper at the front end of the plate *e*.

As seen in the drawing, the heat and products of combustion are allowed to come in contact with the bottom of the pan, but by raising the damper, the flue *g* is closed, and the flue *h* is opened, and the heat will pass beneath the partition.

Upon each side of the fire-box I there are cleats or projecting ribs, *i i*, and

J is a shallow pan which contains water, and rests upon the cleats *i*.

By this means the contents of the lower pan C are prevented from burning when such protection is necessary.

The finishing-pan *J'*, represented in fig. 4, is double, the lower portion, *k*, being designed for water for the protection of the contents of the upper pan, there being a space under and around the sides, for water, so that in finishing the sirup, it is placed in a water-bath, where the temperature cannot rise much, if any, above the boiling-point.

The lower pan *k* receives hot water from a boiler, *L*, on the back part of the stove, through the pipe *m*.

The steam which may be generated may pass out through the pipe *n*, or pass into the pipe *o*, in the pan *J*, and be discharged from the end of that pipe at *p*.

The top or cover of the pan *J'* is perforated for the purpose of retaining the heat, to some extent, while the vapor is allowed to escape freely.

The pan represented in figs. 6 and 7, is designed for cooking fruit or vegetables, its bottom as well as top being perforated.

For boiling-purposes or common use, the finishing-pan *J'* may be removed, and the pan *k* only used.

All the pans may be removed, and the top of the furnace may be covered with plates, having the ordinary cooking-apertures, when the furnace is not used for vaporizing-purposes.

R represents the oven, which is double, with a flue passing around and between the parts, as seen in the drawing.

The vaporizing-pans shown in fig. 1 are constructed with metal bottoms with wooden sides, as seen in the drawing at *S*, but I do not confine myself to that method, although, when the pans are made on a large scale, the expense is considerably reduced by it.

T represents a faucet for drawing off the contents of the pan *J'*.

I claim as new, and desire to secure by Letters Patent—

The furnace A, constructed as shown and described, with the pans B, C, and *J'*, in combination therewith, when the same are constructed and arranged as herein set forth, for the purposes specified.
